UNITED STATES PATENT OFFICE.

JOSEPH LUTHER HART, OF CHICKASHA, OKLAHOMA.

COTTON UNLOADER AND CLEANER.

Application filed August 7, 1915, Serial No. 44,226. Renewed June 19, 1922. Serial No. 569,324.

To all whom it may concern:

Be it known that I, JOSEPH L. HART, a citizen of the United States, and a resident of Chickasha, in the county of Grady and the State of Oklahoma, have invented a certain new and useful Improvement in Cotton Unloaders and Cleaners, of which the following is a specification.

My invention is an improvement in cotton unloading and cleaning apparatus, and the invention has for its object to provide mechanism of the character specified, adapted to be arranged in a gin house or the like, wherein mechanism is provided for unloading the cotton and passing it to a place of storage, and wherein a plurality of cleaning mechanisms is provided, together with means for handling the cotton with fluid under pressure, and so arranged that the cotton may pass from the gin house to the place of storage without cleaning, or the cotton may be subjected to a single cleansing operation or a double cleansing operation, while in either case it is necessary to handle the cotton but once.

In the drawings:

Figure 1 is a diagrammatic view of the entire mechanism;

Figure 2 is a rear view of the cleaning mechanism;

Figure 3 is a section on the line 3—3 of Figure 2, looking in the direction of the arrow adjacent to the line, and

Figure 4 is a vertical section through a modified construction.

The present embodiment of the invention comprises a plurality of cleaners, indicated generally at 1 and 1^a, and to be later described in detail, the casing of the cleaning mechanism 1 having an inlet telescoping pipe 2, for drawing the cotton from a wagon or the like. This casing is also provided with an outlet pipe 5, which is connected at its outer end with the small end of a reducing union 6, and pipes 9 and 18 are connected with the large end of the reducing union.

The pipe 9 is a telescoping pipe, and leads to a suitable source of discharge. The pipe 18 is arched as shown, and the end remote from the union 6 is connected with the large end of a reducing union 13, whose small end is connected with the inlet of the casing of the cleaning mechanism 1^a.

A pipe 15 is also connected with the large end of the union 13, and the outer end of

the pipe 15 is connected to the small end of a union 17. Pipes 20 and 21 are connected with the large end of this union 17, and valves are arranged in the respective unions 6, 13 and 21, for cutting off either pipe connected with the large end of the union from the pipe connected with the small end of the union.

The valves in the union 6, have oppositely extending operating arms 7 and 8, and flexible members, as for instance, cords or wires are connected with the respective arms, a flexible member 10 being connected with the arm 7, while a flexible member 11 is connected with the arm 8. By pulling the proper cord, either pipe 9 or 18 may be cut off from the pipe 5.

The valves in the union 13 have arms 22 and 23 respectively, to which are connected flexible members 24 and 25, and either valve may be operated by pulling the proper cord. The union 17 also has valves, which have arms 26 and 27, and flexible members 28 and 29 are connected with the arms. The operation of these valves is the same as the valves connected with the arms 7, 8, 22 and 23.

The arrangement is such that the cotton may be drawn through the telescoping pipe 2 from the wagon, or other place of supply, into the cleaner casing 1, and from this may pass by way of the pipe 9 to the place of storage, or by way of the pipe 18 to the casing 1^a for a second cleaning operation. When it is desired to use the cleaners 1 and 1^a independently of each other, the valves are arranged to cut off the pipe 18 from both casings 1 and 1^a, that is, from both unions 6 and 13, and to permit the cotton to discharge through the pipe 9. The cotton now feeds by way of the pipe 2 to the cleaner 1 and is discharged by way of the pipe 9. The cleaner 1^a may be fed through the pipe 15 by either pipe 20 or 21.

While the arrangement shown in Figure 1 is the preferred arrangement, it is obvious that the parts might be arranged and combined in any other suitable or desired manner, and other cleaners similar to those indicated at 1 and 1^a might be used. As shown, the cleaners are mounted on a suitable support, alongside each other, and the cotton is thoroughly cleaned as it passes from the wagon to the place of storage. Since the cleaners are precisely the same, and differ only in the manner in which they

are connected together and with the inlet and outlet ports, but a single cleaner will be described, and the said cleaner is shown in detail in Figures 2 and 3.

5 In this construction, the cleaner casing 38 is rectangular in cross section, and is arched or curved longitudinally, and the said casing gradually increases in cross section from the inlet toward the discharge 10 end. The casing is provided with an inlet 39 at the small end, and said inlet is connected with the telescoping pipe 2, or with the union 13.

A screen 40 is arranged longitudinally of 15 the casing, dividing the said casing into two compartments, and the screen is arched to correspond to the casing. The screen extends the entire width of the casing and from the inlet end to near the outlet end, 20 and at the inlet end the adjacent end of the screen is arranged just above the inlet 39.

A bar 41 is arranged transversely of the casing at the inner end of the screen, and 25 the said inner end of the screen is connected with the bar. At this point a shaft 42 is journaled transversely of the casing, and the concave side of the casing is shaped or curved coaxial with the shaft. The 30 casing is branched at this point, to form an outlet 43, for the compartment above the screen 40, and an outlet 44 for the compartment below the screen, and the shaft 42 is arranged just above the outlet 44.

35 The shaft 42 supports a feeding cylinder 45 which is secured to the shaft and consists of a hub 64 having radial blades 65. The casing between the branches 43 and 44 has a re-entrant portion 46, the inner end of which is spaced apart from the bar 41, and a screen 47 is arranged between the bar and the re-entrant portion, the screen being curved on an arc whose center is the shaft 42.

45 A discharge trunk 48 is arranged directly below the shaft 42, and pipes 49 lead from the opposite ends of the trunk. A casing 50 is arranged between the trunk 48 and the casing 38, and the branch 44 of 50 the casing communicates with and opens into the upper end of the casing 50, and the lower end of the casing 50 is provided with a lateral branch 51, and a curved screen 58 is arranged in vertical position between the 55 branch 51 and the body of the casing, the blast from the fan, through 48 and 49 driving the dust and dirt not removed through the screen 40 out to the open space through 51 and not to any fan.

60 A cleaning cylinder 52 is journaled transversely of the casing 50, and has its axis parallel with the shaft 42, and the cylinder cooperates with the screen 58. The shaft 53 and the shaft 42 of the cleaning cylinder are extended beyond their respective

casings, and pulleys 54 and 55 are secured to the respective shafts. A belt 56 connects the pulleys, and the shaft 53 is provided at the opposite end from the pulley 55 with a second pulley 57, which may be connected 70 with a suitable source of power.

In the cleaner casing 1, the pipe 2 is connected with the inlet 39, and a suitable exhaust fan (not shown) is connected with the outlet 43 of the compartment above the 75 screen. The pipe 5 is connected to the trunk 48, or one of the pipes 49. In the casing 1^a the trunk 48 is connected to a pipe leading to the place of storage, and if desired the cotton may be fed directly to the cleaner 80 casing 1^a, by way of the pipe 15.

In operation, the cotton or bolls passes through pipe 2 by air pressure to cleaner casing 1, and the cotton passes down against the screen 40 and 47. The air passes through 85 screen 40 and 47 and out through tube 43 to suction fan, (not shown). The cotton or bolls after passing screen 40 and 47 is fed by flange feed cylinder 45 down into casing 50 and onto cylinder 52 and against screen 90 58. Cylinder 52 carries the cotton downward against screen 58, with considerable force, while the air pressure caused by the discharge of the suction fan (not shown) is pressing against and through screen 58 95 and the cotton as it passes down against screen 58, driven also by force of cylinder 52 against screen 58 assisted by the air pressure is cleaned. The dirt, trash and other foreign matter is forced out through the 100 screen 58 and carried to its destination through pipe 51 by the force of the air. The cotton after cleaning is passed on down by the force of the cylinder 52 into trunk 49, and carried by the exhaust air from suction 105 fan, (not shown) out through pipe 5 to its place of storage or to a second cleaner of a similar kind or any other cleaner or vacuum box through pipe 18.

If desired, the cotton may be passed to 110 the place of storage, by properly manipulating the valves in the union 6. If it is desired to subject the cotton to a second cleaning, the valve in the pipe 9 is closed, and the valve in the pipe 18 is opened. The valves 115 are ordinary gate valves, and it will be evident that the cotton may be thoroughly cleaned before it is ginned.

The removal of the heavier trash is brought about by the toothed cylinder 52 120 and the screen 58. The exhaust air passes around the cleaning cylinder 52 and through the cotton, thus blowing out all of the impurities.

It will be noted that the air pressure moves 125 in the direction of the arrows in Figure 3, the pressure being approximately the same in the pipes 48, 51 and 49. The flow of the cotton below the screen 40 to the cleaning cylinders is, however, assisted not only by 130

gravity but by the operation of the feeding fingers.

In Figure 4 is shown a modified construction of cleaner, wherein the cleaners 68, 69 take the place of the cleaner 52 while the other parts shown in Figure 3, including elements 42—64—65 must still remain in order to separate the suction and blast ends of the fan. In this construction the cotton enters over a breaker bar 73, which is adjustably mounted for movement toward and from a toothed cylinder 68 journaled in the casing 67. The breaker bar is supported by a cross bar 75 and handled screws 74 are threaded through the bar 75 and are rotatably connected to the breaker bar. It will be evident that by means of the cranks the bar may be adjusted toward and from the cylinder. A second toothed cylinder 69 is arranged below and behind the cylinder 68, and the discharge pipe 48 corresponding to the pipe 48 of Figure 3 is below and behind the cylinder 69. Curved screens 70 and 71 are supported adjacent to the cylinders 68 and 69 by means of cross bars 72, and the outlet for the dust 76 is on the opposite sides of the screens from the outlet 48 for the cotton. With this construction the cotton is thoroughly cleaned by the toothed cylinders in co-operation with the screens and the breaker bar, the dust passing out through the outlet 76, while the cleaned cotton passes out at the pipe 48.

I claim:

1. In a cotton cleaner of the character specified, a plurality of cleaner casings, an inlet pipe leading to one of the casings, a delivery pipe leading from the said casing and branching at its outer end, a pipe leading from one branch to a place of storage, a pipe leading from the other branch to the second cleaner casing, valves in the branches, an inlet pipe for the other casing and having branches at its outer end, one of the branches being connected with the last named pipe, an inlet pipe connected with the other branch, and valves for controlling the branches; said last named inlet pipe having branches, and valves for controlling the branches.

2. A cotton cleaner of the character specified, comprising in combination with the pipes for conveying the cotton from the receiving station to the place of storage, and the fluid pressure controlled means for moving the cotton through the pipes, of cleaning mechanism interposed in the length of said pipes for cleaning the cotton during transit, said cleaning means comprising a casing having an inlet at one end and a plurality of outlets at the other end, a screen arranged between the inlet and one of the outlets, and extending longitudinally of the casing, a feeding cylinder arranged between the casing and the last named outlet, a cleaning

cylinder to which the feeding cylinder delivers, a casing for the cylinder having a lateral branch and an outlet, and a screen between the branch and the casing, said screen cooperating with the cleaning cylinder.

3. A cotton cleaner comprising a plurality of cleaners, each of the said cleaners having an inlet for the cotton and the first cleaner having a branched outlet, one of the branches leading to a place of storage and the other leading to the second cleaner, valves for controlling the inlets and outlets, and fluid pressure controlled means for moving the cotton through the cleaners, the inlets and the outlets.

4. In a cotton unloader and cleaner of the class described, a plurality of cleaner casings, an inlet pipe leading to one of the casings, a delivery pipe leading from the said casing and branching at its outer end, a pipe leading from one branch to a place of storage, a pipe leading from the other branch to the second cleaner casing, valves in the branches, for independently opening or closing the same, and an inlet pipe for the other casing and connected with the last named pipe.

5. In a cotton unloader and cleaner of the class described, a plurality of cleaner casings, an inlet pipe leading to one of the casings, a delivery pipe leading from the said casing and branching at its outer end, a pipe leading from one branch to a place of storage, a pipe leading from the other branch to the second cleaner casing, valves in the branches for independently opening or closing the same, and an inlet pipe for the other casing and connected with the last named pipe, said inlet pipe having branches at its outer end.

6. In a cotton unloader and cleaner of the class described, a plurality of cleaner casings, an inlet pipe leading to one of the casings, a delivery pipe leading from the said casing and branching at its outer end, a pipe leading from one branch to a place of storage, a pipe leading from the other branch to the second cleaner casing, valves in the branches for independently opening or closing the same, an inlet pipe for the other casing and having branches at its outer end, one of the branches being connected with the last named pipe, an inlet pipe connected with the other branch, and valves controlling the branches.

7. A combined unloader, cleaner and boll breaker adapted for use as an unloader or unloader and cleaner in connection with air or belt distributers, comprising in combination with the pipes for conveying the cotton from the receiving station to the place of storage and the fluid suction controlled means for moving the cotton through the pipes; of cleaning mechanism interposed in

the length of said pipes for cleaning the cotton during transit, and means to throw the cleaning mechanism out of operation.

8. A combined unloader, cleaner and boll
5 breaker adapted for use as an unloader or
unloader and cleaner in connection with air
or belt distributers, comprising in combination
with the pipes for conveying the cotton
from the receiving station to the place of
10 storage and the fluid suction controlled
means for moving the cotton through the
pipes; of cleaning mechanism, interposed in
the length of said pipes for cleaning the cot-
ton during transit, said cleaning means com-
15 prising a casing having an inlet at one end
and a plurality of outlets at the other end, a
screen arranged between the inlet and one of
the outlets and extending longitudinally of
the casing, said last named outlet being
20 adapted for connection with a suction fan,
a feeding cylinder arranged in the casing
and the last named outlet, a cleaning cyl-
inder to which the feeding cylinder delivers,
a casing for the cylinder having a lateral
25 branch and an outlet, and a screen between
the branch and the casing, said screen co-
operating with the cleaning cylinder, the
branch and outlet of the casing being adapt-
ed to be connected with exhaust or suction
30 fans.

9. A combined unloader, cleaner and boll
breaker, comprising in combination with the

pipes for conveying the cotton from the re-
ceiving station to the place of storage and
the fluid suction controlled means for mov-
35 ing the cotton through the pipes; of clean-
ing mechanism interposed in the length of
said pipes for cleaning the cotton during
transit, said cleaning means comprising a
casing having an inlet at one end and a plu-
40 rality of outlets at the other end, a screen
arranged between the inlet and one of the
outlets, and extending longitudinally of the
casing, the last named outlet being adapted
for connection with a suction fan, and a 45
feeding cylinder arranged between the cas-
ing and the last named outlet.

10. In a combined unloader, cleaner and
boll breaker, the combination with pipes or
like conveying means for conveying the cot-
ton from the receiving station to the place of
storage and fluid pressure controlled means
for moving the cotton through the pipes, of
a plurality of cleaning mechanisms inter-
posed in the length of said pipes for clean-
ing the cotton during transit, and means for
controlling said pipes whereby to cause the
55 cotton to be discharged without passing
through said cleaning mechanism, to pass
through one of said cleaning mechanisms, or
to pass through a plurality or all of said
mechanisms for discharge to the place of
storage.

JOSEPH LUTHER HART.
